[57] **CLAIM**

The ornamental design for a deer butchering rack, as shown and described.

DESCRIPTION

FIG. 1 is a front elevational view of the deer butchering rack showing my new design, the rear elevational view being a mirror image thereof;

FIG. 2 is a left side elevational view thereof, the right side elevational view being a mirror image thereof;

FIG. 3 is a top plan view thereof;

FIG. 4 is a bottom plan view thereof; and,

FIG. 5 is a perspective view thereof.
